US0D1009559S

(12) **United States Design Patent** (10) Patent No.: **US D1,009,559 S**
(45) Date of Patent: ** Jan. 2, 2024

(54) **COOKING GRATE**

(71) Applicant: **Dometic Sweden AB**, Solna (SE)

(72) Inventors: **Samuele Meda**, Chichester (GB); **Birk Söödi**, Johanneshov (SE); **Ramkumar Selvaraj**, Tamil Nadu (IN); **Anoop Muthu**, Kerala (IN); **János Herbály**, Martfű (HU); **Rickard Hederstierna**, Hägersten (SE)

(73) Assignee: **Dometic Sweden AB**, Solna (SE)

(**) Term: **15 Years**

(21) Appl. No.: **29/805,966**

(22) Filed: **Aug. 31, 2021**

(30) **Foreign Application Priority Data**
